TIMER DEVICE FOR LOAD RELEASING MEANS

Filed Aug. 5, 1946

UNITED STATES PATENT OFFICE

2,492,817

TIMER DEVICE FOR LOAD RELEASING
MEANS

John C. Rumsey, Mission, Kans.

Application August 5, 1946, Serial No. 688,478

2 Claims. (Cl. 294—83)

1

The present invention relates to timing devices whereby the operation of other mechanism or devices is withheld from taking place for a given predetermined interval, which may be varied or adjusted within suitable limits.

A special purpose of the invention is to provide an effective timing device for automatic load-releasing appliances of the type used in aerial transportation and which are operative to maintain a continuous and reliable holding and supporting connection with the load and also include means operating to insure a proper release of said supporting connection at the landing point or place of delivery of the load.

One important feature of the improved device is the provision of timing means which will be adapted to preserve a safe interval between the time of first application of the load as transmitted and under the pull of the parachute or carrier (following its release for landing purposes), and the final operation of the load-releasing means at the landing point or place of delivery of the load.

With the foregoing general objects in view, the invention will now be described by reference to the accompanying drawing illustrating one practical and yet simple form of construction which has been devised and found suitable for the efficient embodiment of the proposed improvements, after which those features and combinations deemed to be novel and patentable will be particularly set forth and claimed.

In the drawing—

Figure 1 is a longitudinal sectional view, illustrating a load releasing appliance equipped with timing means constructed in accordance with the present invention;

Figure 2 is a detail sectional view, representing a section taken on the line 2—2 of Figure 1; and

Figure 3 is a similar detail view, representing a section taken on the line 3—3 of Figure 2.

The present application relates to improvements in the subject matter set forth in my copending application Serial No. 681,395, filed July 3, 1946, now Patent No. 2,489,819, dated July 3, 1946.

Accordingly the present drawing shows a load releasing appliance comprising a casing member 10 provided with a swivel link 12 for attachment to the cable or other supporting means suspended from a parachute or other transporting carrier (not shown). The casing 10 serves as a housing for enclosing a pair of coil spring elements, including a compression spring 14

2

which is seated in and permanently secured within the lower end of said casing, and also a strong tension spring 18 the upper end of which has an attachment 20 designed for detachable engagement with notches or recesses 22 formed at the upper end of a longitudinal slot 24 provided along one side of said casing 10. This slot 24 permits the insertion of said spring 18 into the interior of the casing for removable latching and releasing purposes; and the lower end of said spring 18 is provided with an attachment 26 making connection with a loop 28 designed to serve as a means of connection to the load which is to be releasably carried by the appliance.

The compression spring 14 is designed to serve as a yielding cushion for certain of the parts after these have been assembled in the operative and latched relationship illustrated, with the spring 18 enclosed within the casing 10. In this relation the spring 18 is maintained under a given tension by having its upper end anchored by means of the attachment 20 and its lower end drawn down by the link 28 and the latter then latched after having applied a certain degree of pressure to the other spring 14.

The lower portion of the casing 10 is formed with a pair of diagonal slots 30 on opposite sides of the longitudinal 24, for accommodating the movement of the crossbar portion of attachment 26 when assembling the parts in relation just described.

The latching means for retaining the parts in the aforesaid relation consists of a semicylindrical element 32 pivoted at 34 to the sides of the casing 10 and formed with notches 36 in its lower edge for latching engagement with said crossbar portion of the attachment 26. A leaf spring 38 is attached as indicated at 40 to the upper end of said latch element 32 and tends to actuate the latter normally outward into unlatched position; a loop or keeper 42 on the casing 10 serves to limit said outward movement of the latch element 32.

A leaf spring 45 is also anchored at 46 within the top portion of the casing 10, with the lower end of said spring extending in position for engagement with the attachment 20 supporting the spring 18, and exerting thereon a pressure sufficient to dislodge said attachment from the notches 22 when the pull on the spring 18 falls below a given tension.

In the operation of the appliance as so far described and as outlined in my aforementioned pending application, the load is designed to be

supported with the weight thereof divided between the springs 14 and 18—the latter being pulled down under tension and the spring 14 supporting the balance of the load under compression. The parts are assembled initially and maintained in the said relation by the latching means above described, with said springs maintained under certain degrees of compression and tension respectively, and this latching means is sufficiently secure to allow all the necessary handling of the appliance, preparatory to operation under load, as when dropped for a parachute landing. When this takes place and the load is therefore taken up by a pull on the link 28, the spring 14 is still further compressed, with the result that the latch 32 is released and therefore becomes automatically disengaged from the attachment 26 of the load supporting link 28. Thereafter during the continued flight of the load the same is supported by the joint action of the two springs 14 and 18, and hence any variation in the pull of the load will be automatically accommodated by corresponding or compensating spring action, within a given limit as represented by a predetermined minimum pull of the load. Such predetermined limit corresponds to a retraction of the spring sufficient to bring the crossbar of attachment 26 to the upper end of the slots 30, when the pressure tending to hold the attachment 20 in position will be overcome by the action of the spring 45, which accordingly acts to eject or dislodge said attachment from the notches or recesses 22, thus leaving the parts carrying the load entirely unsupported and free, as explained in said copending application.

It is apparent that under some conditions, following the aforesaid disengagement of the link 28 from the latch element 32 and the release of the latter, abnormal air currents may be encountered which may relieve the load on the springs and produce such variations in the pull of the load as to cause an untimely or premature disengagement of the upper spring 18 from its support and without any actual ground contact for landing purposes.

Accordingly I have devised an improved timing device which will insure a predetermined time interval to elapse before any actual release of the latching element is allowed to take place. For this purpose I provide a detent arm 50 pivoted at 52 to a bracket 53 attached to the lower portion of the casing 10 and having a knee portion 54 for engagement with the latch element 32. The free end of the arm 50 is adapted for sliding engagement through a loop or eye 56 formed on the end of a rod 58 projecting through an opening 59 in a housing member 60 which is fixedly mounted on the side of the casing 10, said rod having its inner end secured to a transverse bar portion 62 operating slidingly through slots 64 in the sides of the housing 60. The inner end of the rod 58 is also connected with a coil spring 66 attached to the interior of the housing as indicated at 67 and operating to normally retract the rod within the casing for disengaging and releasing said detent arm 50. The retracting pull of said spring, however, is regulated by frictional means, comprising a block of suitable compressible material (such as a block 70 of natural rubber) which is formed with a groove 71 for embracing the rod 58 as indicated in Figures 2 and 3. The rubber block 70 is attached (as indicated at 72) to the end of a spring leaf 74 attached by rivets 75 or the like to the interior of the housing 60. The degree of

pressure exerted by said block upon the rod 58 is regulated by an adjusting screw 76 threaded through the wall of the housing into engagement with the leaf 74, and provided with a suitable clamping nut 78.

From the foregoing it will be seen that a definite and adjustable timing drag may be imposed upon said rod 58 whereby the release of the detent arm 50 may be deferred for a predetermined interval, and the start of this interval is further controlled by means of an additional device comprising a detent element 80 pivoted at 82 to the side of the housing 60 in position for engagement with one end of the bar portion 62; and this detent element 80 is also connected with a link 84 operating slidingly through a suitable keeper element 86 and terminating in a hook portion 88 in the path of movement of the crossbar portion of the aforesaid attachment 26.

By means of this construction it will be seen that the same movement of the attachment which releases the latch element 32 also operates the detent 80 (by a pull on the link 84) to simultaneously release the crossbar 62 and thereby initiate the operation of the timing device; and as a consequence the final release of the detent 50 for also releasing the latch member 32 can not take place until after full retraction of the rod 58 as controlled by the timing device. Consequently a full interval of time (as set by the adjustment of said timing means) must elapse, following the start of the parachute drop, before any final release of the load supporting connections comprising the loop 28, attachment 26 and the supporting spring 18, can occur, such time interval being of course regulated by the adjustment of the screw 76 to embrace a sufficient period of time to guard against any premature release of the load due to abnormal air conditions as above referred to.

The end portions of the crossbar 62 are provided with guiding washers 63, and their terminals may be formed with suitable finger loops 65 (see Figure 2) adapted to facilitate the setting of the timer device with one end portion of said crossbar in latching engagement with the detent 80, as will be readily understood.

From the foregoing it will therefore be apparent that I have devised a practical, simple and highly efficient arrangement and construction for the carrying out of the aforesaid objects on my invention, including the provision of a compact and efficient type of timing means for regulating the operation of the load releasing appliance. It will moreover be obvious that the function of said timing device will be found very useful and practical in various other relations, aside from that shown in operative relation to load releasing appliances. I therefore desire to be understood as expressly reserving the right to such other uses and applications of my improvements, as well as to all changes or modifications therein which may be fairly deemed to fall within the spirit and scope of my invention as defined by the appended claims.

Having described my invention, what I claim is:

1. Load releasing means for releasing loads from parachute carriers and the like, comprising a main body member for attachment to the carrier, a link for attachment to the load and provided with a coil supporting spring detachably connected with said body member, means operating automatically as the load on said spring imposes thereto a given minimum tension for effect-

ing detachment thereof from said body member, and timing means operating automatically as said spring is subjected to its maximum tension under the load for blocking said detaching operation for a given time interval.

2. Load releasing means for releasing loads from parachute carriers and the like, comprising a main body member for attachment to the carrier, a link for attachment to the load and provided with a coil supporting spring detachably connected with said body member, means operating automatically as the load on said spring imparts thereto a given minimum tension for effecting detachment thereof from said body member, and timing means operating automatically as said spring is subjected to its maximum tension under the load for blocking said detach-

ing operation for a given time interval and including detent means released simultaneously as said spring reaches its maximum tension under the load for starting the operation of said timing means.

5 JOHN C. RUMSEY.
